(57) **CLAIM**

The ornamental design for a golf divot repair tool, as shown and described.

DESCRIPTION

FIG. 1 is a top front perspective view of a golf divot repair tool showing my new design;

FIG. 2 is a front elevation view thereof, with a rear elevation view being a mirror image of the front elevation view;

FIG. 3 is a right elevation view thereof;

FIG. 4 is a left elevation view thereof;

FIG. 5 is a top elevation view thereof, with a bottom elevation view being a mirror image thereof; and,

FIG. 6 is an exploded top front perspective view thereof. The line shading shown in the drawings depicts curved surfaces. The broken lines shown in the drawings depict portions of the article that form no part of the claimed design.

1 Claim, 3 Drawing Sheets
